CLAIM

The ornamental design for a boat motor cover, as shown and described.

DESCRIPTION

FIG. 1 is a perspective view of the boat motor cover;

FIG. 2 is a right view thereof;

FIG. 3 is a left view thereof;

FIG. 4 is a front view thereof;

FIG. 5 is a back view thereof;

FIG. 6 is a top view thereof; and,

FIG. 7 is a perspective view of the boat motor cover in relation to a boat motor frame and another cover.

The ornamental design, which is claimed, is shown in solid lines in the drawings. Any broken lines in the drawings are for illustrative purposes of the boat motor cover and form no part of the claimed design.
